Primary Examiner — Paula Greene(74) *Attorney, Agent, or Firm* — Sughrue Mion, PLLC(57) **CLAIM**

The ornamental design for a speaker, as shown and described.

DESCRIPTION

FIG. 1 is a perspective view of the front, top and right side of a speaker showing my new design;
FIG. 2 is a perspective view of the rear, bottom and left side thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom view thereof.

The broken line showing of the speaker is included for the purpose of illustrating portions of the speaker and forms no part of the claimed design.

1 Claim, 4 Drawing Sheets(56)
